UNITED STATES PATENT OFFICE.

JOHN SCHUMACHER AND JOSEPH E. SCHUMACHER, OF LOS ANGELES, CALIFORNIA.

PLASTER-BOARD OR THE LIKE.

1,327,446.

Specification of Letters Patent.

Patented Jan. 6, 1920.

Application filed May 22, 1918. Serial No. 236,040.

To all whom it may concern:

Be it known that we, JOHN SCHUMACHER and JOSEPH E. SCHUMACHER, both citizens of the United States, residing at Los Angeles, in the county of Los Angeles and State of California, have jointly invented new and useful Improvements in Plaster-Board or the like, of which the following is a specification.

10 This invention relates to an improved article of manufacture, namely, wall board, plaster board, or the like, which is used in building construction in place of the ordinary lath or metal lath, and as a wall element in and by itself, or a wall element to receive a finishing coat of plaster or a covering of paper or any other finishing and surfacing material or substance suitable or preferable. Such plaster board or wall board, in the usual or best practice, comprises a suitable composition disposed between surface or facial sheets of paper or other flexible material, and, as we make such 15 plaster board or wall board, such plastic substance or composition is supplied to and between such facial sheets of paper or the like, and the sheets and the composition are united under pressure, and produced in any suitable or feasible lengths, which may be 20 cut up, shaped or subdivided as desired, and given any particular conformation as best adapts them for purposes of decoration or to fit them to any particular design or scheme of construction. In order to insure perfect 25 adhesion of the plaster or other facial coating applied to such plaster board as stated, and to cause such facial coating to be retained in contact with the plaster board without fracture or separation or buckling 30 or displacement, it is a common practice to provide for the interlocking of such surface covering or mass thereof with the plaster board. To this end, projections or pro- 35 tuberances are sometimes formed, standing out from the plaster board, and at other times openings are formed in the plaster board, into which openings the plaster coat-

ing or wall material may penetrate to form interlocking keys or studs. The projections or buttons or the like referred to protrude into the plaster material and act as interlocking buttons or studs. In any case, when the composition of the plaster board is exposed to produce such buttons or projections or form such openings, even if it only be by cutting away the paper or other covering of the composition, the access of the moist plaster or wall material to the composition of the plaster board is permitted, and the moisture thereof tends to soften the composition of the plaster board between the two facial sheets, or such moisture even tends to penetrate the sheets themselves, and soften them and likewise soften the composition of the board, the result being that the board is weakened and has a tendency to bend or buckle or bulge or otherwise lose its true form, due to the weight of the adhering plaster coating upon it when so softened or weakened by the invading moisture. This results in either a failure of the plaster board, possibly even to the extent of its 40 crumbling or breaking, or the plaster board's detachment from the building frame or stud- 45 ing, or the detachment of the plaster or wall material from the plaster board, or the bulging or warping or buckling or other disturbances of the proper condition of the plaster wall material. To prevent these objectionable occurrences and the possible failure of the wall board or plaster board to stand up and hold up the plaster wall covering, and to prevent the sagging or buckling or bulging of the plaster wall covering and the presentation of an unsightly appearance, and even the possible displacement of the plaster wall covering from the plaster board, we have found it expedient to apply to the plaster board or wall board, at any point at which the composition of the plaster board is exposed, a suitable moisture insulating or water-proofing material or composition, such as tar paint, rubber compound, or other suitable substances,

Likewise, it at times is found advantageous to also apply such moisture insulating or water-proofing substance to the paper sheets themselves which constitute the facial portions of the plaster board. In this manner the moisture of the wall covering or plaster is entirely withheld from access to and invasion of the composition of the plaster board, and in the latter instance likewise 10 withheld from penetration of the paper covering of the plaster board, and the plaster board or wall board retains its full unimpaired strength and maintains its true and proper form, and is not softened or 15 weakened in any manner, nor in any manner so softened or weakened as to permit it to withdraw from the building frame.

Furthermore, this insulating or water-proofing of the plaster board over its entire 20 surface or over the exposed portions of the composition, or both, prevents the access to the composition of the plaster board of any moisture which may invade the wall covering itself even after it has set and hardened 25 and dried. Thus, the plastered walls of a building constructed with plaster board elements, would be able to withstand subjected to moisture from rainwater, fire hose or other source, and the wall maintain its integrity. 30

The importance of thus preserving the wall board or plaster board from invasion by moisture, in any manner, will be seen from the foregoing statements, and our invention consists in the provision of a wall board or plaster board element, or the like, suitably organized so that the composition of the board is insulated against moisture, or water-proofed as stated. 35

40 The invention has for its objects the provision of an improved article of manufacture, consisting of plaster board, or wall board, which will be in whole or partially water-proofed as above pointed out, and 45 which will be superior in point of relative inexpensiveness and simplicity of construction and organization, and convenience in manufacture, durability, length of life, freedom from disintegration, and which will be 50 generally superior in efficiency and serviceability.

With the above and other objects in view, the invention consists in the novel and useful formation, construction, composition, organization and structure of parts, features, and of the whole, all as hereinafter described, shown in the drawing, and finally pointed out in claims. 55

In the drawing:

60 Figure 1 is a fragmentary sectional view of a length or sheet of plaster board insulated against moisture or water-proofed in accordance with the present invention;

Fig. 2 is a similar view showing a modified 65 form of construction;

Fig. 3 is a similar view showing a still further modified form of construction;

Fig. 4 is a similar view showing a still further modified form of construction;

Fig. 5 is a similar view showing a still 70 further modified form of construction;

Fig. 6 is a facial plan view of the construction shown in Fig. 5;

Fig. 7 is a view similar to Figs. 1 to 5 inclusive, showing a still further modified 75 form of construction; and

Fig. 8 is a similar view showing a still further modified form of construction.

In Figs. 1, 2, 4, 7 and 8, the composition of the wall board or plaster board is shown 80 as cut or broken away or recessed or penetrated to provide for invasion of the plaster or wall covering to cause same to interlock with the plaster board in key fashion. In Fig. 3 the plaster board is shown as provided with a projecting stud to interlock 85 with the plaster or wall covering. In Figs. 5 and 6 the paper covering of the plaster board is shown as cut or broken away to expose the insulated composition of the plaster 90 board, and in Fig. 6 the paper covering is shown as broken away in part to expose the composition of the board.

Corresponding parts in all the figures are designated by the same reference characters. 95

Referring with particularity to the drawing, A in each instance designates the body material or composition of the plaster board, which may be of any preferred or suitable organization, including a cementitious or 100 plastic substance admixed with any other material that may be desired to produce the proper body strength of the board and give it the necessary qualities. B in each instance designates the facial covering of paper or 105 the like, between which coverings the plastic or cementitious or composition body A is disposed. This may be applied to one or both faces of the body A, and such paper or 110 surface covering and the body may be associated and brought together and caused to unite or adhere in any suitable manner, as by passing the unstable body material to and between sheets of paper and uniting the entirety under the pressure of suitable rollers. 115 These matters are not material to the present invention which concerns a water-proofing or moisture-insulating element C which is applied to the plaster board wherever the body or composition A is exposed, or is applied both to such exposed portions of the body and to the surface or paper covering B. In the form shown in Fig. 1 the body A is recessed as at 9 through from one face to the facial covering B at the other face and 120 the insulating material or water-proofing material is applied to all of the exposed body portions and to all exposed surfaces of the surface coverings B, and to the edges or ends of the plaster board over the body 125 130

and the paper covering. In the form shown in Fig. 2, the plaster is provided with a through opening 10, and the water-proofing material C is applied to the thus exposed body material A and to the entire walls of the opening and the surface covering B. In the form shown in Fig. 3, the body material A is projected through the paper covering to form a button or protuberance 11, and the water-proofing material is applied entirely over such button and over the facial coverings B. In the form shown in Fig. 4 a through opening 12 is provided and the water-proofing material is applied as described in connection with Fig. 2, with the exception that tongues or fingers 13 are provided at one end of the opening 12, being produced in cutting through the paper covering at the respective side of the plaster board. In the form shown in Figs. 5 and 6 the paper at one face of the board is cut away as at 14 to expose the body material A, and such body material which is thus initially exposed is covered with the water-proofing material C, as is the surface of each facial covering B.

In Figs. 7 and 8 through openings 15 and 16 are shown provided in the plaster board, and these are shown roughened so as to provide particularly efficient interlocking engagement with the plaster of the wall which invades such openings. These roughened walls of the opening are covered with the water-proofing material C, all the way through the opening and the opening 16 in Fig. 8 is shown as slightly tapered to produce a possibly more efficient interlocking key action with the plaster.

It will be seen that in each of these forms the body A, wherever otherwise exposed, is covered with or treated with the moisture insulating or water-proofing material C, which may consist of water-proof paint, tar paint, rubber composition, or plaster or plastic material, water-proofed by any suitable process or in any suitable manner. In certain forms, as in Fig. 1, the entire plaster board unit or element is shown as water-proofed or moisture-insulated, over its entire surface and its ends, and edges, and in its recess for interlocking with the wall covering, so that moisture is withheld from access to any part or surface of it. The degree of water-proofing, or the points or surfaces to which the water-proofing material is applied or water-proofing treatment is given, may be varied as desired, in accordance with the requirements of the particular work or service of the plaster board or the particular nature of the covering or plaster, and the extent to which the water-proofing is efficient may be varied, so that the moisture may be excluded entirely or for a greater or lesser period of time, as for instance, sufficiently to permit the plaster cov-

ering to set and harden prior to any possible softening of the plaster board.

It will be noted by utilizing the invention that it becomes possible to entirely prevent the softening and weakening of the plaster board or wall board which might otherwise cause it to be displaced from a building frame, or cause it to warp or buckle or bend or disintegrate or in turn cause the plaster covering to warp or buckle or bend or disintegrate or fall or lose its proper smooth, flat appearance.

It is manifest that many changes and variations and adaptations of the invention may be made, over and beyond and in distinction from the specific disclosure of the drawing and the description just made, in adapting the invention to varying conditions of use and service and to obtain the varying objects and purposes, all within the true spirit of the invention.

Having thus disclosed our invention, we claim and desire to secure by Letters Patent:

1. Plaster board or the like, comprising a body provided with a surface covering which is in part interrupted, said body at the zone of such interruption being water-proofed.

2. Plaster board or the like, comprising a body provided with a surface covering which is in part interrupted, said body at the zone of such interruption being water-proofed; said surface covering being likewise water-proofed.

3. Plaster board or the like, comprising a body portion and facial covering, said facial covering being interrupted, and said plaster board being water-proofed at said zone of interruption, at the ends or edges, and at the surface covering.

4. Plaster board or the like, comprising a body portion and a surface covering, the surface covering being interrupted and the body portion formed to interlock with the plastic wall material, and said body portion where so formed being water-proofed.

5. Plaster board or the like, comprising a body portion and a surface covering, the surface covering being interrupted and the body portion formed to interlock with the plastic wall material, and said body portion where so formed being water-proofed; said surface covering being likewise water-proofed.

6. Plaster board or the like, provided with a recess for interlocking with a plastic wall material; the walls of said recess being water-proofed.

7. Plaster board or the like, provided with a recess for interlocking with a plastic wall material; the walls of said recess being water-proofed; said recess extending through the plaster board.

8. Plaster board or the like, provided with a recess for interlocking with a plastic wall

material; the walls of said recess being water-proofed; said recess extending through the plaster board and having roughened or irregular walls.

5 9. Plaster board or the like, provided with a recess for interlocking with a plastic wall material; the walls of said recess being water-proof; said recess extending through the plaster board and having tapered walls.

10 10. Plaster board including facial sheets, plastic filler between the sheets, one of the

said sheets being perforated and the plastic filler being exposed through the perforations, and water-proofing applied to the 15 exposed portions of the plastic filler.

In testimony whereof we have signed our names to this specification in the presence of two subscribing witnesses.
